UNITED STATES PATENT OFFICE.

JOHN M. CASE, OF COLUMBUS, OHIO, ASSIGNOR TO THE CASE MANUFACTURING COMPANY, OF SAME PLACE.

GRADUAL-REDUCTION MACHINE.

SPECIFICATION forming part of Letters Patent No. 417,629, dated December 17, 1889.

Application filed March 30, 1887. Serial No. 233,013. (No model.)

To all whom it may concern:

Be it known that I, JOHN M. CASE, a citizen of the United States, residing at Columbus, in the county of Franklin and State of Ohio, have invented certain new and useful Improvements in Gradual-Reduction Machines, of which the following is a specification.

The invention consists in certain features of novelty, which are hereinafter particularly pointed out in the claim, being first fully described with reference to the accompanying drawings, in which—

Figure I is an elevation of the head end of the machine. Fig. II is a vertical transverse section on the line II II, Fig. III, looking toward the tail end of the machine. (See arrow.) Fig. III is a vertical longitudinal section on the line III III, Fig. I, looking in the direction of the arrow. Fig. IV is an elevation of the tail end of the machine. Fig. V is a horizontal section on the line V V, Fig. IV, looking downward. Fig. VI is a detail view, on a larger scale, showing fragments of the adjacent faces of the rolls. Fig. VII is a diagram, hereinafter more particularly referred to. Fig. VIII is a detail view of a conveyer of modified form, hereinafter referred to.

The object of the present invention is to combine in a single portable machine of small dimensions all those devices and appliances for effecting the several steps necessary in the gradual reduction of grain.

The machine is designed more particularly for use in those localities where large mills are scarce, (because not profitable,) and it is constructed on such a scale as to be capable of being driven by horse or even, if need be, by hand power.

The machine comprises a grain-cleaner, two pairs of reduction-rolls, a pair of bolts, and suitable cut-offs, spouts, and conveyers, whereby the material is caused to pass from the cleaner to the first break-rolls, thence to the first bolting-reel, by which it is separated into flour, unfinished middlings, and bran, which are separately drawn off, the unfinished middlings being delivered to the second break-rolls, whence it passes to the second bolting-reel, whereby the remaining bran and other impurities are drawn off and the better

product separated into flour of two, three, or more grades.

On the upper part of the machine is placed a wheat-cleaner consisting of a corrugated scouring-drum 1, placed within a closed cylindrical casing 2, having at one end a hopper 3 for the reception of the grain and at the other end an aperture through which the grain escapes. The end of the cleaner terminates with its discharge-aperture in a vertical air-trunk 4, open at its lower end and communicating above the discharge-aperture with the eye of a fan 6, mounted upon the same shaft which carries the scouring-drum. The fan-casing is placed in close proximity to the delivery end of the scouring wheat-cleaner and the air-trunk 4, carried over the top of the casing and down on the other side, communicating with the eye of the fan remote from the cleaner. This arrangement is adopted with a view to making the machine as compact as may be. The lower end of the air-trunk 4 communicates with a spout 7, through which the cleaned grain passes downward to the hopper 8, placed over the first break-rolls 9 9^a, Figs. III and V, the bottom of said spout being formed of a sheet of wire-gauze 7^a, through which foreign substances of greater specific gravity than the dust may sift, and through which air may enter for supplying the fan. The air in rushing through the air-trunk 4 carries with it all light dust and other impurities. The roll 9 is driven at a higher speed than the roll 9^a, and has its teeth inclined in a direction opposite to the direction in which its surface moves, while those of the roll 9^a are inclined in a direction the same as that in which its surface moves (see Fig. VI)—that is to say, viewing both rolls from the end the teeth of both will be seen to project in the same direction relative to their respective axes, while the teeth on the contiguous faces of the two rolls will be seen to project in opposite directions, those of the fast roll being presented upward and those of the slow roll downward. The result of this arrangement is that the grain is crushed against the inclined back surfaces of the teeth, as shown in Fig. VI, rather than cut, as it would be if

the arrangement of the teeth here shown were reversed. These rolls which I employ in this mill are short axially but large in diameter. The effect of increasing the diameter is to increase in a vertical direction the superficial area of each roll, which is at all times within grinding distance of the other. This will be apparent on reference to the diagram, Fig. VII, where *a* represents grain to be crushed and the circles *b b* represent the peripheries of a pair of rolls of small diameter. It will be observed that the superficial area of each of these rolls which is within grinding distance of the other extends from the point *x*, where they most nearly approach each other, to the point where the grain will have contact with both rolls, (represented by the line *y*.) Now, referring to the lines *c c*, which represent the peripheries of a pair of rolls of larger diameter, it will be observed that the superficial area of each which is within grinding distance of the other (ascertainable in the manner already illustrated with reference to the smaller rolls) is much greater, extending from *x* to *z*. By thus greatly increasing the diameter of the rolls the bran will be finished by the first break and may be almost completely removed by the first bolting-reel 10, to which the material is conveyed by a spout 11. This bolt is clothed with bolting material having meshes of different size for separating the material into three or more grades, the grades shown in Fig. III being preferred.

The cloth at the head of the bolt is designed to pass only the flour which is produced by the first break, which falls into the conveying-trough beneath the bolt, and is carried by the conveyer 11^a toward the head of the machine, where it is drawn off by a spout 12. The next section of the bolt is clothed with cloth a little finer than that at the head for preventing the specks from passing through after the good flour is all drawn off. The next section is clothed with bolting material with mesh of sufficient size to permit the passage of all the unfinished middlings, arresting only the bran, which tails off and is carried off by a spout 13 for feed. The middlings passing through the last section of the bolt fall into the conveyer-trough and are carried by the same conveyer 11^a toward the head of the machine. The trough of this conveyer is provided at close intervals with cut-offs 14, for drawing off the material falling therein at any desired point or points, and in the treatment of the grain which is now being described the cut-off is opened between the first and second sections of the bolt, so that the material passing through the second and third sections will fall into the conveyer-trough beneath and be carried by the conveyer 15 to the tail end of the machine and delivered into the bottom of a vertical spout 16, containing a vertical conveyer or elevator 17. I have shown two conveyers, one 11^a for carrying the material toward the head of the machine, and the other

15 for conveying toward the tail of the machine, with cut-offs for the passage of the material from the upper to the lower trough; but where it is always desired to make the cut-off at the same place, thus rendering superfluous more than a single one of the cut-offs 14 here shown, a single conveyer may be employed, consisting of a shaft with the 70 blade on opposite sides of the point where it is desired to make the separation inclined in opposite directions, as shown in Fig. VIII. For example, if it be desired always to separate the material at the point beneath the 80 tail end of the first section of the bolt, the blade would be twisted from this point in opposite directions toward the respective ends of the shaft, so as to feed the material falling through the first section of the bolt toward 85 the head and that falling through the second and subsequent sections toward the tail end of the machine. This double form of conveyer is well known, and need not be further explained here.

The form of the vertical conveyer or elevator is not material, the one here shown consisting of an endless belt with buckets secured thereto at intervals, which scoop up the material from the bottom of the vertical 95 spout 16 and deliver it at top into an inclined trough or spout 18, through which it passes into the hopper 19 (see Fig. III) of the second break-rolls 20 20^a.

20 is the fast roll, being secured to a long 100 shaft 21, to which the fast roll 9 of the first break-roll is secured, while the roll 20^a is secured to a similar shaft 22, to which the slower roll 9^a of the first break-rolls is secured.

The material after passing the second break-rolls is conducted through a spout 23 into the head of a second bolt 24, which is divided off similarly to the bolt 10, but clothed with cloth of different numbers. The second 110 break-rolls are either smooth or of very fine scratch, and are so adjusted as to effect a complete reduction of the middlings, so that the bolt 24 is clothed to separate the product into as many grades of finished flour as may 115 be desired, what little bran or other impurities may remain in it being tailed off. The material passing through the bolt 24 falls into a conveyer-trough containing a conveyer 120 25, the trough being provided at close intervals with cut-offs similar to the cut-offs 14 already described for making any desired number of separations. I prefer to clothe this bolt with cloth No. 12 at head, No. 13 in the center, and No. 10 at tail, for making three 125 separations of the product passing therethrough, the cut-offs of the conveyer-trough being arranged to keep the several grades separate.

26 is a second conveyer placed beneath the 130 conveyer 25 for assisting in carrying out the separation of the different grades of flour.

Each pair of rolls is inclosed within a separate housing, one of the walls of which

is formed by offsets 60 in the casing of the machine, the other consisting of a separate partition 27. These housings are constructed with hopper-bottoms, with which the spouts 11 and 23, respectively, communicate. The two pairs of rolls are located at different ends of the machine, (the first break-rolls being located at the head and the second break-rolls at the tail,) and the head of each bolt is located directly beneath the pair of rolls which it serves, the bolts being thus arranged to tail off in opposite directions.

The boxes of the slow rolls are here shown as fixed, while the boxes of the fast rolls are movable and have applied to them the means for adjusting the distance asunder of the rolls; but this arrangement may be reversed without departing from my invention. As heretofore stated, the two movable rolls are secured near the respective extremities of one common shaft 21, and this shaft turns in journal-boxes 28, mounted to slide on suitable bearings on the casing. Each of these boxes is forced toward the fixed roll, so as to hold the surfaces of the rolls in working position by a spring 29, the tension of which may be adjusted by a set-screw 30, tapped into a lug 31, projecting upward from the casing. Tapped into each of these lugs 31 is also a hand-screw 32, which is so connected at its inner end as to regulate and determine the distance to which the rolls shall approach each other, and at the same time permit them to separate when any foreign substance or even when grain is delivered to them in such excess of their grinding capacity so as to overcome the resistance of the springs 29. These screws may also be used for separating the rolls and holding them apart, so as to permit stock to pass in the event of a choke-up.

It will be observed that by making the rolls short, as already described, and securing them to the ends of a pair of shafts much longer than the rolls themselves, (or, at least so securing the movable rolls,) a single pair of adjustable boxes and mechanism for adjusting them is made to serve two pairs of rolls, each of which, according to the usual construction, requires a pair of such adjusting devices. I do not herein claim any details in the construction of this adjusting mechanism, as any of the old and well-known arrangements for this purpose may be employed.

33 represents the main driving-belt, which passes around a pulley 34, fixed to the shaft 21 of the fast rolls at the tail end of the machine.

35 represents a belt which passes over a smaller pulley 36, secured to the end of the shaft 21 outside of the pulley 34, and also over a pulley 37, secured to the upper shaft of the elevator 17.

38 is a belt at the head of the machine, which passes around a pulley 39, secured to the shaft 21, a second pulley 40, of very large diameter, secured to the shaft of the first bolt 10, a third pulley 41, of the same diameter as

the pulley 40, secured to the shaft of the second bolt 24, and under a belt-tightening pulley 42, secured to a swinging arm 43, which is pivoted to the end of the casing and engaged by a set-screw 44, by which the arm 43 may be swung on its pivot for tightening the belt.

45 is a crossed belt at the tail end of the machine, which passes around a pulley 46, secured to the shaft of the second bolt 24, and a pulley 47, secured to the extremity of the shaft 22 of the slow rolls.

48 is a belt at the head of the machine, passing around a pulley 49, secured to the shaft 80 22 of the slow rolls 9 and 20 within the plane of the pulley 39, and around a pulley 50, secured to the shaft which carries the fan and the scouring-drum.

51 is a belt at the tail end of the machine, 85 which passes around a pulley 52, secured to the shaft of the bolt 10, and around a second pulley 53, secured to the shaft of the conveyer 11.

54 is a pinion secured to the shaft of the 90 conveyer 11 at the head of the machine and meshing with a pinion 55, secured to the shaft of the conveyer 15.

56 (see Fig. IV) is a belt at the tail end of the machine passing around a pulley 57, secured to the shaft of the second bolt 24 within the plane of the pulley 46, and around a second pulley 58, secured to the shaft of the conveyer 25.

The conveyer 26 is driven from the conveyer 25 through means of pinions 54^a and 55^a, Fig. I, located at the tail end of the machine, similarly to the pinions 54 and 55, through the medium of which the upper conveyer 11 drives the lower conveyer 15.

It will be seen that with this system of belts, pulleys, &c., the entire mill is driven from a single prime motor, the various pulleys being so proportioned as to give the desired relative velocity to each of the several parts.

Having thus described my invention, the following is what I claim as new therein and desire to secure by Letters Patent:

In a portable gradual-reduction machine, 115 the combination, with a suitable casing, of a grain-scourer and an air-trunk, a fan and a suction-spout communicating with the discharge of the grain-scourer, all located on top of one end of the casing and having a spout 120 communicating with the interior of the casing, directly below a pair of horizontal shafts centrally located in the upper part of the casing, said shafts carrying, respectively, co-operating fast and slow grinding-rolls located on their 125 opposite ends in tight housings formed in offsets in the casing by suitable partitions, said pairs of rolls being dressed as first and second break-rolls, and the first break-rolls being directly beneath and fed by the spout 130 from the scourer, a pair of graded sifting-bolts located centrally beneath and parallel to the shafts of the rolls, tailing in opposite directions, and each being fed by a spout

from the grinding-rolls adjacent its head, a pair of collectors and separating-conveyers located beneath the respective bolts and having suitable spouts, a hopper located on top of the casing at the opposite end to the grain-scourer and feeding the second break-rolls, and an elevator communicating between the tailing from the bolt of the first break-rolls

and the hopper for feeding the second break-rolls, all substantially as and for the purposes to set forth.

J. M. CASE.
